UNITED STATES PATENT OFFICE.

MARTIN BALCKER, OF CHICAGO, ILLINOIS, ASSIGNOR TO MARQUETTE TOOL & MANUFACTURING COMPANY, OF CHICAGO, ILLINOIS, A CORPORATION OF ILLINOIS.

LOCKING DEVICE FOR PRESSURE PADS OF DOUBLE-ACTING POWER PRESSES.

1,409,149.

Specification of Letters Patent.

Patented Mar. 14, 1922.

Application filed January 28, 1921. Serial No. 440,049.

To all whom it may concern:

Be it known that I, MARTIN BALCKER, a citizen of the United States, residing at Chicago, in the county of Cook and State 5 of Illinois, have invented certain new and useful Improvements in Locking Devices for Pressure Pads of Double-Acting Power Presses, of which the following is a specification.

- 10 This invention relates to improvements in locking devices particularly adapted though not necessarily limited in its use, for locking the pressure pad or beam of a double acting power press, equipped with fluid controlled die cushions, and has for one of its 15 objects to provide an improved means for automatically locking together the blank holder or gripping rings and the pressure pad or beam whereby they will be caused 20 to rise together, and improved means for automatically unlocking them so that the draw or gripping ring cage or support may be lowered independently of the pressure pad or beam.
- 25 To the attainment of these ends and the accomplishment of other new and useful objects as will appear, the invention consists in the features of novelty in substantially the construction, combination and arrangement of the several parts hereinafter 30 more fully described and claimed and shown in the accompanying drawings illustrating this invention and in which—

Figure 1 is a view partly in elevation, 35 partly in section and with parts omitted of a portion of a double acting die press having this improvement applied thereto and showing the mechanism in the positions which they will assume before the press has 40 started its operation and with the pressure pad or beam in its elevated position.

Figure 2 is a view similar to Figure 1 showing the parts in the positions they will assume just at the completion of the forming operation.

Figure 3 is a detail sectional view taken on line 3—3, Figure 2.

Figure 4 is a detail end elevation of a portion of the press.

50 Figure 5 is a view in detail as taken on line 5—5, Figure 7.

Figure 6 is a detail sectional view taken on line 6—6, Figure 8.

55 Figure 7 is an enlarged detail view partly in elevation and partly in section of the

locking mechanism with the parts in the position shown in Figure 2.

Figure 8 is a view similar to Figure 7 with the parts in the position they will assume as shown in Figure 1.

Referring more particularly to the drawings the numeral 10, designates generally the die supporting base or bolster upon which is arranged the die 11, having a movable portion 12. Projecting above the 65 bolster 10, are the usual uprights 13, upon which the draw ring cage 14, is adapted to be reciprocated in the ordinary and well known manner. The draw ring 15, is carried by the cage 14, and is adapted to co-operate with the portion 11, of the die for holding the material 16, in position, in a manner well known in this art. The punch 17, is adapted to be reciprocated in the ordinary and well known manner within the draw or 70 gripping ring 15, independently with respect to the movement of the draw ring.

Arranged beneath the bolster 10, is a cushion beam or element 18, and in the form of the invention herein shown there is connected with this cushion beam or element a plurality of piston rods 19, connected with piston members (not shown) reciprocable within the cylinders 20. These cylinders 20, are supported in any suitable manner such 80 as by means of the supports 21, and fluid is adapted to be delivered into the cushions from any suitable source of supply, by means of suitable pipe connections 22, so that a fluid pressure will operate upon the 90 cushion beam or element 18. Passing through suitable guides, such as a portion of the bed or bolster 10, are pins 23, which engage the movable element 12, of the die or forming means and also engage and rest 95 upon the cushion or pressure beam 18, so that when the fluid is admitted into the cylinders 20, on one side of the pistons it will operate the pistons to raise the beam or element 18, and through the medium of 100 the pins 23, raise the element 12, of the forming die, and when pressure is exerted upon the material 16, by the punch 17, the element 12, will be lowered against the pressure of the fluid in the cylinders 20, through 105 the medium of the pins 23, all as well known in this art.

In shaping articles with presses of this character it is desirable to hold the work or article by the gripping or draw ring 15, 110

co-operating with the portion 11, of the die, permitting the punch 17, to be withdrawn before the material is released and before the article is ejected from the die. If this 5 operation is not performed then the operation of the ejecting means for the article would have a tendency to rip or strip the flanges from the article. In order to overcome this difficulty the automatic locking 10 means hereinafter described has been provided and as has been before stated this automatic locking means operates to lock together the blank holder or gripping ring 15, and the pressure beam or element 18, 15 so that they will be caused to rise together after the punch has been withdrawn and also to automatically unlock the draw or gripping ring cage 14, and the cushion beam or element 18, so that the draw or gripping 20 ring cage 14, and draw or gripping ring 15, may be lowered independently with respect to the cushion beam or element 18.

To that end there is provided on each 25 end of the cushion beam or element 18, an automatically operating locking means and as the construction of the locking means and its connection with the draw ring cage on each end of the beam or element 18, is the same, the description of one will apply 30 equally as well to both of them.

Arranged within the end of the beam or element 18, is a housing 24, having a cam 25, therein and which cam is mounted for pivotal movement upon a shaft 26, preferably 35 passing through the cam and through the walls of the housing. This cam is provided on a portion thereof with a series of teeth or projections 27, adapted to engage and mesh with a series of teeth 28, carried by an element 29, which latter passes loosely through 40 the top 30, and bottom 31, of the housing 24. Connected with the draw ring cage 14, is a bar or rod 32, which is of any desired length, the lower extremity 33, thereof being preferably 45 rectangular in cross section and of any suitable hardened material. This section 33, is adapted to be connected with the bar or rod 32, in any suitable manner such as by means of a tongue or projection 34. The extremity 33, of the bar or rod passes loosely 50 through the top 30, and bottom 31, of the housing 24, similar to the element 29, but on the side of the cam adjacent the active edge 55 of the cam so that when the cam is moved about its pivot by means of the shifting of the element 29, the active surface thereof will be brought into frictional contact with the face of the extremity 33, of the bar or rod 32, for frictionally locking together the draw 60 ring cage 14, and the cushion beam or element 18.

The element 29, projects for any desired distance above the beam or element 18, and is provided with a shoulder 36, preferably 65 adjacent one end thereof. A housing 37, is

provided with an opening 38, in the bottom thereof through which the element 29, loosely passes so that the shoulder 36, will stand within the housing and may engage and rest upon the bottom thereof. The housing is 70 preferably provided with a removable closure 39, and an elastic element 40, such as a coil spring is arranged within the housing with one end thereof resting against the shoulder 36, of the element 29, and the other 75 end engaging the closure 39. The normal tendency of the spring 40, is to maintain the shoulder 36, of the element 29, against the bottom of the housing and interposed between the bottom of the housing, on the outside thereof and the top of the beam or element 18, is another elastic element 41, preferably in the form of a coil spring which encompasses the element 29, with one of its ends engaging and resting against the bottom of the housing and the other end engaging and resting against the top of the beam or element 18. It will thus be seen that the housing 37, is supported by the elastic element 41, for movement with the element 29, 90 and the element 29, and the housing 37, are also adapted for movement one with relation to the other, in a manner to be hereinafter described.

Carried by any suitable fixed support, 95 preferably the bolster 10, and within the path of movement of the housing 37, is an adjustably mounted stop device or bolt 42, which is adapted to be engaged by the closure 39, of the housing 37, for arresting the 100 movement of the housing and thereby imparting a relative movement to the housing and the element 29. This stop device 42, is readily accessible so that it may be adjusted to any desired or necessary extent to vary the time at which a relative movement will be imparted to the element 29, and housing 37, with respect to the movement of the beam or element 18.

In operation, and assuming that the parts 110 are in the position shown in Figure 1, and the work 16, is in place upon the die 11, the cam 25, will be moved out of contact with the portion 33, of the bars or rods 32, and the cushion beam or element 18 will be in its uppermost position with the closure 39, of the housing 37, in contact with the end of the stop device 42, with the spring or elastic members 40-41 placed under compression. 115

When the press is operated the draw ring cage 14, will be lowered, causing the draw or gripping ring 15, to move into contact with the work 16, to grip the same upon the die 11. Inasmuch as the cushion beam or element 18, is unlocked from the cage 14, the 120 latter will move independently of the former and the ends 33, of the bar or rod 32, will slide freely through the housing 24. As soon as the punch 17, is lowered and begins to operate upon the work 16, a further movement 125 130

of the punch will move the element 12, of the die and through the medium of the pins 23, the cushion beam or element 18, will be lowered against the pressure of the fluid in the 5 cylinders 20. This lowering movement of the beam or element 18, will operate first to permit the elastic elements 40—41 to expand or exert their stress upon the element 29, in such a manner as to shift the element 29, 10 with respect to the beam or element 18, in a direction to rotate the cam 25, about its pivot and thereby cause the active edge thereof to frictionally grip the surface of the portion 33, of the bar or rod 32, and thereby lock the 15 cage 14, for movement with the element 18. As the two elements are thus locked together and as the beam or element 18, continues in its lowering movement the closure 39, of the housing 37, will move away from the stop 20 device 42, and further as the beam or element 18, is lowered it will be cushioned in its lowering movement by means of the compression of the fluid in the cylinders 20.

The parts will then be in the position 25 shown in Figures 2 and 7, and will remain in this position until after the forming operation and until the punch 17, is withdrawn from the work. When the cage 14, is raised it will, inasmuch as it is locked 30 with the beam or element 18, rise with the latter and the two will be locked together until the closure 39, of the housing 37, abuts the end of the stop 42, and this will occur slightly before the beam or element 18, 35 reaches the limit of its upward movement. A further movement of the beam or element 18, in the same direction, will cause the housing 37, to be arrested in its movement by reason of its engagement with the stop 40 42, but the element 18, will travel further for a short distance in the same direction. This will cause a compression to be exerted upon the springs or elastic elements 40—41 and the spring 41, will then be rendered 45 ineffective with the result that through the medium of the spring or elastic element 40, and the housing 37, the element 29, assumes such relative positions that after the cam 25, is started in its rocking movement, the 50 spring 40, will then shift the element 29, with respect to the beam or element 18, to further rotate the cam device 25, from its locking position shown in Figure 7, to the position shown in Figure 8, thereby unlocking 55 the cage 14, and the beam or element 18, to permit the former to move independently of the latter. The movement of the portion 33, of the bar or rod 32, with respect to the beam or element 18, will start 60 the rocking of the cam 25, about its pivot into an inoperative position and the expansion of the spring element 40, when the parts are thus released, will continue the rocking movement of the cam 25, until it 65 assumes the position shown in Figure 8.

Thus it will be seen that the beam or element 18, will be automatically locked and unlocked with respect to the draw ring cage 14, to permit the latter to move with the former and also independently with respect 70 thereto and this automatic locking and unlocking is effected at predetermined points in the travel or movement of the draw ring cage 14, and also of the beam or element 18.

When it is desired to change or adjust 75 the die upon the bed or bolster 10, unless some means is provided for locking the beam or element 18, the latter will drop to its lowermost position thereby causing considerable inconvenience and annoyance. In 80 order therefore to maintain this element or beam 18, in its raised or uppermost position, when it is unlocked from the cage 14, or when the beam or element 18 assumes the position shown in Figures 1 and 8, there is 85 provided a locking device which will maintain the cam 25, in its ineffective position with respect to the bar or rod 32. Any suitable locking device may be provided for this purpose but a simple and efficient lock 90 embodies a bar or rod 43, which is preferably carried by the beam or element 18, and extends upwardly therefrom to project through and move in an opening 44, in the bolster 10. This bar or rod 43, is connected to the beam 95 or element 18, for axial rotation in any suitable manner such as by means of collars 45—46. A lug or projection 47, is connected with the bar or rod 43, and the upper extremity of the bar is preferably provided with an angular portion 48, for the reception of a tool or implement by means of which the bar or rod 43, may be rotated with respect to the element 18, to shift the lug or projection 47. 100

The housing 37, is provided with a laterally projecting portion 49, having a bifurcation 50, in one of its edges to form spaced shoulders. This bifurcation 50, receives the bar or rod 43, and the latter serves as a 110 guide for maintaining the housing 37, against rotation with respect to the element 29. This locking device is normally maintained ineffective but when it is desired to lock the parts in the position shown in 115 Figure 8, the lug or shoulder 47, will stand above the projection 49, on the housing and by rotating the rod 43, this projection 47, may be positioned to extend across and rest upon the projection 49, as shown more 120 clearly in Figure 6. When it is desired to unlock the parts this rod is rotated so as to move the projection 47, so that it will pass through the bifurcation 50.

The upper surface of one of the ears forming the bifurcation 50, of the projection 49 may, if desired be provided with an inclined surface 51, and the lower surface of the lug or projection 47, may also be provided with an inclined surface 52, so as to assist 125 130

in the manipulation of the rod 43, the upper surface of the other ear of the bifurcated portion being preferably flat as at 53, to form a stop shoulder 54, to limit the rotation 5 of the rod 43, in one direction.

Throughout the specification and claims, the locking device 25, has been designated as a cam; but it is to be understood that any kind of a locking element other than cam, 10 and which is suitable for the purpose may be employed, and therefore the term cam as herein used is not to be construed as a term of limitation.

While the preferred form of the invention 15 has been herein shown and described it is to be understood that various changes may be made in the details of construction and in the combination and arrangement of the several parts, within the scope of the claims, 20 without departing from the spirit of this invention.

What is claimed as new is:—

1. In combination, a die press embodying co-operating shaping members, means for 25 holding the material while being shaped, the said means embodying a holding element and a movable element for actuating the said holding element, a cushion element operating upon one of the said shaping members, fluid pressure means operating upon the said cushion element, means for automatically locking together the said holding element and the said cushion element whereby they will be caused to move together, and means for automatically unlocking them so that the said holding element may be moved independently of the 30 said cushion element.

2. In combination, a die press embodying 40 co-operating shaping members, means for holding the material while being shaped, the said means embodying a holding element and a movable element for actuating the said holding element, a cushion element operating upon one of the said shaping members, fluid pressure means operating upon the said cushion element, means for automatically locking together the said holding element and the said cushion element whereby 45 they will be caused to move together, and means controlled by the movement of the said cushion element for automatically unlocking the said cushion element and the said holding element so that the holding element 50 may be moved independently of the said cushion element.

3. In combination, a die press embodying co-operating shaping means, means for holding the material while being shaped, the said 60 means embodying a holding element and a movable element for actuating the holding element, a cushion element operating upon a portion of the shaping means, fluid pressure means operating upon the said cushion element, means embodying a shiftable cam 65

element for automatically locking together the said holding element and the said cushion element whereby they will move together, teeth on said cam, a shiftable toothed element for actuating the cam, means operating automatically to shift the said toothed element in one direction to render the cam active, and means for shifting the said toothed element in the opposite direction to render the cam ineffective. 70

4. In combination, a die press embodying co-operating shaping means, means for holding the material while being shaped, the said means embodying a holding element and a movable element for actuating the 80 holding element, a cushion element operating upon a portion of the shaping means, fluid pressure means operating upon the said cushion element, means embodying a shiftable cam element for automatically locking together the said holding element and the said cushion element whereby they will move together, teeth on said cam, a shiftable toothed element for actuating the cam, means operating automatically to shift the 85 said toothed element in one direction to render the cam active, and means adapted to automatically shift the said toothed element in the opposite direction at a predetermined point in the movement of the said 90 cushion element to render the said cam ineffective.

5. In combination, a die press embodying co-operating shaping means, means for holding the material while being shaped, the said 100 means embodying a holding element and a movement element for actuating the holding element, a cushion element operating upon a portion of the shaping means, fluid pressure means operating upon the said cushion element, means embodying a shiftable cam element for automatically locking together the said holding element and the said cushion element whereby they will move together, teeth on said cam, a shiftable toothed element for actuating the cam, means operating automatically to shift the said toothed element in one direction to render the cam active, means for shifting the said toothed element 105 in the opposite direction to render the cam ineffective, and additional means for locking the said toothed element in one of its shifted positions. 110

6. Locking device for pressure element for double acting power press and embodying a 120 pressure element, fluid controlled means acting thereupon, a reciprocable element, means operating automatically to lock the said elements together to cause them to move together, and means for automatically unlocking them so that the said reciprocable element may be moved independently of the 125 said pressure element.

7. Locking device for pressure element for double acting power press and embodying a 130

- pressure element, fluid controlled means acting thereupon, a reciprocable element, means operating automatically to lock the said elements together to cause them to move together, and means for automatically unlocking them so that the said reciprocable element may be moved independently of the said pressure element, both of the said means embodying a cam, teeth on the cam, a shiftable toothed element for moving the cam, and a plurality of means rendered active at different points in the movement of the pressure element for shifting the toothed element.
8. Locking device for pressure element for double acting power press and embodying a pressure element, fluid controlled means acting thereupon, a reciprocable element, means operating automatically to lock the said elements together to cause them to move together, means for automatically unlocking them so that the said reciprocable element may be moved independently of the said pressure element, both of the said means embodying a cam, teeth on the cam, a shiftable toothed element for moving the cam, a plurality of means automatically rendered active at different points in the movement of the pressure element for shifting the said toothed element, and positive means for locking the said toothed element in one of the positions into which it has been shifted.
9. A locking device for pressure element for a double acting power press and embodying a pressure element, fluid controlled means acting thereupon, a reciprocable element, means embodying a cam for locking the said elements together, a shiftable element for actuating the said cam to render the same effective and ineffective, and opposed elastic means operable upon the said toothed element for controlling its direction of movement, the said elastic means being respectively rendered active at different predetermined points in the movement of the said pressure element.
10. A locking device of the character described embodying two elements reciprocable one with relation to the other, fluid pressure means operating upon one of the elements, a toothed cam device carried by one of the elements and adapted to co-operate with the other element for locking the said elements for movement together, a shiftable toothed element carried by one of the first said elements for actuating the cam, opposed spring elements operable upon the said toothed element for moving it in opposite directions to render the cam effective and ineffective, and means for rendering one of the said spring elements effective and the other of the said spring elements ineffective at a predetermined point in the movement of one of the first recited elements.
11. A locking device of the character described embodying two elements reciprocable one with relation to the other, fluid pressure means operating upon one of the elements, a toothed cam device carried by one of the elements and adapted to co-operate with the other element for locking the said elements for movement together, a shiftable toothed element carried by one of the first said elements for actuating the cam, opposed spring elements operable upon the said toothed element for moving it in opposite directions to render the cam effective and ineffective, and means for rendering one of the said spring elements effective and the other of the said spring elements ineffective at a predetermined point in the movement of one of the first recited elements, the last recited means embodying a fixed stop for arresting the movement of the said toothed element with the one of the first elements by which it is carried.
12. A locking device of the character described embodying two elements reciprocable one with relation to the other, fluid pressure means operating upon one of the elements, a toothed cam device carried by one of the elements and adapted to co-operate with the other element for locking the said elements for movement together, a shiftable toothed element carried by one of the first said elements for actuating the cam, a shoulder on the toothed element, a member slideable upon the toothed element on one side of the shoulder, an elastic member operating upon the said member and tending normally to move the member against said shoulder to shift the toothed element in one direction, a portion of the said member extending to the other side of and being spaced from said shoulder, an elastic element disposed between the said portion and the said shoulder and adapted to be rendered effective for shifting said toothed element, and means for shifting the said member with relation to the toothed element for rendering one of the said elastic elements effective and the other elastic element ineffective.
13. A locking device of the character described embodying two elements reciprocable one with relation to the other, fluid pressure means operating upon one of the elements, a toothed cam device carried by one of the elements and adapted to co-operate with the other element for locking the said elements for movement together, a shiftable toothed element carried by one of the first said elements for actuating the cam, a shoulder on the toothed element, a member slideable upon the toothed element on one side of the shoulder, an elastic member operating upon the said member and tending normally to move the member against said shoulder to shift the toothed element in one direction, a portion of the said member ex-

tending to the other side of and being spaced from said shoulder, an elastic element disposed between the said portion and the said shoulder and adapted to be rendered effective for shifting said toothed element, and a fixed stop arranged in the path of movement of the said member with the one of the first recited elements which supports the said member for shifting the said member with

respect to the said toothed element to render 10 one of the said elastic elements effective and the other of the elastic elements ineffective with relation to the said toothed element.

In testimony whereof I have signed my name to this specification, on this 20th day 15 of January, A. D. 1921.

MARTIN BALCKER.
